To all whom it may concern:

Be it known that I, Abraham Solomon, a citizen of the United States, residing at New York city, county and State of New York, have invented a new, original, and ornamental design for a Cocktail Shaker, of which the following is a specification, reference being had to the accompanying drawing, forming part thereof.

The characteristic features of the design re-

I claim:

The ornamental design for a cocktail shaker, substantially as shown and described.
